The ornamental design for an optical lens for a vehicle light as shown and described.

DESCRIPTION

FIG. 1 is a perspective view of an optical lens for a vehicle light, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and

FIG. 7 is a bottom plan view thereof; and,

FIG. 8 is a perspective view thereof, showing in an environment of use.

The claimed design is indicated by the relatively dark portions in the figures, while the relatively light portions form no part of the claimed design.
